Primary Examiner — Ryan Harvey(74) *Attorney, Agent, or Firm* — Steven M. Koehler; Westman, Champlin & Koehler, P.A.(57) **CLAIM**

The ornamental design for a bicycle trainer, as shown and described.

DESCRIPTION

FIG. 1 is a perspective view of a bicycle trainer. FIG. 2 is a top view of the bicycle trainer of FIG. 1. FIG. 3 is a bottom view of the bicycle trainer of FIG. 1. FIG. 4 is a front view of the bicycle trainer of FIG. 1. FIG. 5 is a rear view of the bicycle trainer of FIG. 1. FIG. 6 is a right view of the bicycle trainer of FIG. 1; and, FIG. 7 is a left view of the bicycle trainer of FIG. 1. The broken lines of FIGS. 1-7 are included for the purpose of illustrating environmental structure and form no part of the claimed design.
